UNITED STATES PATENT OFFICE.

ETHAN I. DODDS, OF PITTSBURGH, PENNSYLVANIA, ASSIGNOR TO FLANNERY BOLT COMPANY, OF PITTSBURGH, PENNSYLVANIA.

STAY-BOLT STRUCTURE.

1,403,744.

Specification of Letters Patent. Patented Jan. 17, 1922.

Application filed January 20, 1920. Serial No. 352,691.

To all whom it may concern:

Be it known that I, ETHAN I. DODDS, a citizen of the United States, and a resident of Pittsburgh, in the county of Allegheny, and State of Pennsylvania, have invented 5 certain new and useful Improvements in Stay-Bolt Structures; and I do hereby declare the following to be a full, clear, and exact description of the invention, such as 10 will enable others skilled in the art to which it appertains to make and use the same.

This invention relates to improvements in staybolt structures for boilers and particularly to means for mounting the head of the 15 staybolt in the outer boiler sheet,—one object of the invention being to provide a simple and efficient structure comprising two members removably connected together, which may have an adjustable mounting relatively 20 to the boiler sheet and be welded to the latter when adjusted, and which shall be capable of being so connected with the outer boiler sheet that its outer end may be substantially flush with the outer face of said sheet or of 25 being so mounted as to project beyond the outer face of the boiler sheet.

A further object is to provide a two-part structure comprising a bearing member and closure which shall be so connected and associated that either or both may be seated 30 in the opening in the boiler sheet.

With these and other objects in view, the invention consists in certain novel features of construction and combinations of parts 35 as hereinafter set forth and pointed out in the claims.

In the accompanying drawings; Figure 1 is a sectional view, partly in elevation, showing an embodiment of my invention; Figure 40 2 is a view showing another manner in which the devices may be mounted in the opening in the boiler sheet; Figures 3 and 4 are views showing different ways of mounting a modified structure, and Figures 5 to 45 18 are views showing various modifications.

1 represents a boiler sheet having an opening 2, the major portion of the wall of which may be straight and substantially cylindrical, but the wall of the opening in the 50 boiler sheet is rounded near its inner end, near the inner face of the boiler sheet, to form a rounded seat 3 for a bearing structure (as hereinafter described) in which the rounded head 4 at the outer end of a stay-bolt 5 is mounted,—the inner end of the

staybolt being secured to the inner boiler sheet 6 in any suitable manner.

The bearing structure above referred to, comprises a bearing ring 7 having an internal rounded seat 8 for the rounded head of the 60 staybolt, and a hollow member 9 approximately semi-elliptical in cross-section, the latter being threaded interiorly, as at 10, to receive the threaded peripheral portion of the bearing ring. The member 9 constitutes a closure 65 over the bolt head and is so formed as to provide a clearance space 11. A gasket 12 is located between one end of the bearing ring 7 and a shoulder 12 in the closure member 9.

The closure member 9 is rounded exteriorly, as at 13, and has a universally movable or adjustable mounting on the rounded seat 3 in the boiler sheet, and said closure member may also be provided with an angular portion 14 to receive a wrench.

By so mounting the bearing structure in the opening in the boiler sheet that it may be universally movable, it may be readily adjusted to insure accurate alignment of 80 the staybolt with its point of connection with the respective boiler sheets.

It will be observed that in the embodiment of the invention shown in Figure 1, the bearing structure is so mounted in the opening in 85 the outer boiler sheet that its outer end will be substantially flush with the outer face of said sheet. That portion of the opening in the boiler sheet between the outer portion of the closure member 9 and the straight wall 90 of said opening will form an annular space and within the inner portion of this space, a weld 15 is located (when the bearing structure shall have been properly adjusted), said weld overlying a portion of 95 said closure member and fixedly uniting the same to the wall of the opening in the boiler sheet.

In the embodiment of the invention shown in Figure 2, the bearing structure is so 100 mounted in the boiler sheet as to project beyond the outer face of the latter. In this instance, the inner portion of the opening 16 in the boiler sheet may have a straight wall, but the other portion of the wall of said 105 opening is rounded, as at 17, and both the closure member and the bearing ring have universally movable mountings on said rounded seat, the inner end portion of the ring being made with a rounded face 18 110

for this purpose in the same arc as that of the rounded portion 10 of the closure member. When the bearing structure is thus mounted, it will be welded to the outer face 5 of the boiler sheet by a weld 19 which surrounds the closure member of said structure.

In the construction shown in Figure 3, the boiler sheet 1 is provided with a tapering opening 20, the inner portion of the wall of which 10 is slightly curved to provide a seat 21 for a closure member 22 which is so located in the opening in the boiler sheet that its central portion will be substantially flush with the outer face of the boiler sheet.

15 The closure member shown in Figure 3 is approximately semi-elliptical in cross section, presenting a curved or rounded peripheral portion 23 so that the structure may have a universally adjustable mounting on 20 the seat afforded by the wall of the opening in the boiler sheet. The portion 23 of the closure member is threaded internally for the reception of the bearing ring 24 in which the head of the staybolt is mounted, and said 25 bearing ring is formed with a shoulder 25 to receive the edge of the closure member. The face 26 of the bearing ring is rounded in the same arc as that of the portion 23 of the closure member. A weld 27 within 30 the opening in the boiler sheet unites the structure to the latter.

The bearing structure shown in Figure 4 is the same as that shown in Figure 3, but in Figure 4 the wall of the opening in the 35 boiler sheet is made to form a rounded seat 28, and the bearing structure is so mounted on this seat that both members 22 and 24 engage the same and are thus mounted so as to be universally adjustable. In Figure 40 4 the closure member 22 is united to the outer face of the boiler sheet by a weld 29.

In the construction shown in Figure 5, the bearing ring only has a universally movable mounting in the opening in the 45 boiler sheet and the closure member 30 is made conical and beveled at 31, both of said members being united to the boiler sheet by a weld 32. By making the closure member conical, it may be mounted in a conical opening in the boiler sheet 50 when a "flush" mounting is desired, and welded to the sheet at the beveled portion 31.

In the embodiment of my invention shown in Figures 6 to 11, 1 represents an outer 55 boiler sheet and 2^a an inner boiler sheet, with which latter, the inner end of a stay-bolt 3^a is connected in any suitable manner and said bolt is provided at its outer end with a head 4^a which may be connected with 60 the outer boiler sheet as hereinafter described.

In Figure 6, the outer boiler sheet 1 is provided with an opening 5^a, a portion of which 65 may be cylindrical and has a diameter appreciably greater than that of the

staybolt which passes through it, and a portion of said opening is enlarged and rounded to form a rounded seat 6^a.

7^a represents a bearing sleeve or member, the inner end portion of which may be 70 rounded to provide a rounded exterior portion 7^b which may have a universally movable or adjustable mounting on the rounded seat 6^a in the boiler sheet, and a rounded interior seat 8^a on which the rounded head of the 75 staybolt has its mounting. The outer end portion of the bearing sleeve is threaded externally as at 9^a and receives the internally threaded flange 10^a of a one-piece closure member 11^a. A gasket 12^a may be disposed 80 between the closure member 11^a and the outer end of the bearing sleeve 7^a.

The peripheral portion of the closure member and its flange are rounded, as indicated at 13^a and 14^a (the rounded portion 13^a 85 being, in effect, a beveled edge) and said closure member may be made with an angular recess 15^a to receive a wrench.

When the bearing structure is mounted as shown in Figure 6, (in which the bearing 90 sleeve is universally adjustable on its seat in the boiler sheet to insure proper alignment of the staybolt with its points of connection with the respective boiler sheets), a weld 16^a surrounding said sleeve unites 95 the same with the outer face of the boiler sheet.

When a "flush" mounting is desired, the structure may be mounted in the boiler sheet as shown in Figure 7. The outer boiler 100 sheet is here shown as provided with an opening 17^a, a portion of the wall of which may be made tapering and the inner portion of said wall may be made slightly curved to form a seat 18^a for the rounded portion 14^a of the closure member 11^a, the major portion of the latter being located 105 within the opening in the boiler sheet with its outer end substantially flush with the outer face of said sheet. Thus it will be 110 seen that in Figure 7, the closure member 11^a has a universally adjustable mounting in the opening in the boiler sheet and that the strain exerted by the bolt on the bearing sleeve is sustained by the closure member. 115

The rounded portion 13^a of the closure member cooperates with the straight outer portion of the wall of the opening in the boiler sheet to form a groove in which a 120 weld 19^a is located and serves to fixedly unite the closure member to the boiler sheet, after any necessary adjustment of the bearing structure shall have been effected.

In the construction shown in Figure 8, a 125 bearing sleeve 20^a is provided near its upper or outer end with a rounded seat 21^a for the rounded head 4^a of the staybolt, said head being shown as ovoid in shape, and the boiler sheet 1 is made with an opening 22^a which 130

may be cylindrical throughout its major portion,—the outer end portion of the opening being enlarged and its wall rounded to form a seat 23^a for the rounded exterior portion

5 of the bearing sleeve. The bore of the opening in the bearing sleeve may be made flaring from the seat 21^a to the inner end of said sleeve as indicated at 24^a. The closure member 11^b shown in Figure 8 is made with 10 a peripheral portion 25^a having a part surrounding the bearing sleeve and threaded thereto and the outer edge of said peripheral portion may be beveled as shown at 26^a.

The closure member 11^b is formed therein 15 with an angular enlargement 27^a to receive a wrench. The peripheral portion 25^a of the closure member is made with a transversely rounded face 28^a.

When the bearing sleeve is mounted as 20 shown in Figure 8, it will be united to the boiler sheet (after having been properly adjusted) by a weld 29^a, surrounding said sleeve.

The bearing structure shown in Figure 9 25 is the same as that shown in Figure 8, but in the arrangement shown in Figure 9, the opening in the boiler sheet is so formed as to present a rounded wall extending nearly through the sheet, whereby a rounded seat 30^a is formed on which the peripheral portion of the closure member has a universally adjustable mounting, and the outer end of the closure member will lie substantially flush with the outer face of the outer boiler sheet. The outer end portion of the opening 35 in the boiler sheet is beveled as at 31^a and this beveled face forms, with the beveled portion 26^a of the closure member, a groove which receives a weld 32^a,—said weld fixedly uniting the closure member to the 40 boiler sheet.

In the construction shown in Figure 10, the bearing member 33 is made with a plain rounded outer face and may have a universally adjustable mounting on the seat formed by the rounded wall 34 of the opening in the boiler sheet. When thus mounted and properly adjusted the bearing member will be welded to the boiler sheet as at 35. 50 The bearing member is threaded internally and receives a threaded annular flange 36 projecting from and forming part of the closure member 37, the latter being constructed to be mounted in and secured to the boiler sheet in the same manner as 55 shown in Figure 9, where a "flush" mounting is desired.

It will be observed that the rounded portions of the closure members which seat on 60 the wall of the opening in the boiler sheet mark segments of circles which are different from the segments marked by the rounded exterior portions of the bearing members.

In some positions on the boiler structure, 65 it may be found desirable to substitute a

small plug closure for the closure member shown in Figure 10. Such a plug closure is shown at 38 Figure 11 screwed into the bearing member 33.

In the embodiment of the invention as 70 shown in Figure 14, the outer boiler sheet 1 is provided with an opening 5^b, a portion of which is curved transversely of the sheet to provide a rounded seat 6^b for a bearing structure. The said bearing structure comprises a bearing sleeve or member 7^c having an internal rounded seat 8^b for the bolt head and an exterior rounded portion 9^b concentric with the rounded seat 6^b in the opening in the boiler sheet, and a closure member 10^b. A portion of the bearing sleeve is threaded exteriorly to enter the threaded interior of the closure member, as indicated at 11^c, and said closure member is rounded exteriorly as at 12^b. The rounded portion 12^b of the closure member and the rounded portion 9^b of the bearing sleeve may be curved in the same arc, so that when the structure is mounted in the opening in the boiler sheet, both members 7^c and 10^b may 90 have a universally adjustable mounting on the rounded seat 6^b in the boiler sheet. When the structure shall have been properly adjusted to insure accurate alignment of the staybolt with its points of connection with the respective boiler sheets, it will be welded steam-tight to the outer boiler sheet by a weld 13^b surrounding the closure member.

The closure member has an approximately 100 semi-elliptical shape in cross section, with an annular flange 14^b, the edge portion of which is beveled as at 15^b.

When the mounting is to be employed as a "flush" structure, the opening 16^b in the boiler 105 sheet may have a portion 17^b of its wall straight and a portion near the inner face of the sheet, rounded as at 18^b, as shown in Figure 15. The mounting will be disposed in this opening in the boiler sheet so that 110 the rounded portion 12^b of the closure member will have a universally adjustable bearing on the seat 18^b in the boiler sheet, and the flanged portion of said closure member disposed within the opening 16^b and approximately 115 flush with the outer face of the outer boiler sheet. The beveled edge 15^b of the flange 14^b will now form, with a portion of the wall 17^b of the opening 16^b, a groove in which a weld 19^b is located, said weld fixedly 120 uniting the flange of the closure member to the boiler sheet, and sealing the structure steam-tight in the opening in the boiler sheet.

It will be observed that where the flange 125 14^b joins the body of the closure member, the metal is comparatively thin. This will permit of the flange being cut off with the use of a chisel or other tool as indicated by dotted lines 20^b, Figure 15, when it becomes 130

necessary to withdraw the mounting to remove a broken bolt from the boiler.

In the embodiment of the invention shown in Figure 12, the outer boiler sheet is provided with an opening, a portion of the wall of which is rounded to form a seat 5^a and another portion of said wall may be straight as shown at 6^a. A cap 7^a, the outer face of which may lie flush with the outer face of the boiler sheet 1, is provided with an inwardly projecting flange 8^a having a rounded exterior face 9^a to conform to the curvature of the seat 5^a in the boiler sheet so that said cap 7^a may be universally movable within the opening in the boiler sheet. The cap 7^a may be rounded or beveled exteriorly adjacent to the flange 8^a and this portion of the cap may be thickened somewhat and provided interiorly with screw threads 10^a. The outer end portion of a bearing member 11^a enters within the flanged portion of the cap and is threaded interiorly for the reception of a plug 12^a—the inner end of which is separated from a shoulder 13^a in the bearing member by a gasket 14^a and the outer end of said plug extends beyond the outer end of the bearing member and is screwed to the threaded portion 10^a in the cap 7^a. A gasket 15^a may be interposed between the outer end of the bearing member 11^a and the cap 7^a. The bearing member 11^a is provided interiorly with a seat 16^a for the head of the staybolt and the plug 12^a is recessed to form a clearance space 17^a over the head of the staybolt.

By mounting the cap 7^a within the opening in the boiler sheet so that it may be universally adjustable and supporting the bearing member by said cap through the medium of the plug 12^a, the bearing member may be adjusted to insure proper alignment of the staybolt with its points of connection with the respective boiler sheets. Between the rounded or beveled edge portion of the cap 7^a and the portion 6^a of the wall of the opening in the boiler sheet, a weld 18^a is located and unites said cap to the boiler sheet.

When the bearing member 11^a is mounted in the boiler sheet so as to project beyond the outer face of the latter, said boiler sheet may be provided with an opening 19^a having a portion of its wall rounded as at 20^a to receive the rounded portion 21^a of said bearing member, as shown in Figure 15. The bearing member will then be united to the boiler sheet by a weld 22^a and the cap 7^a may be omitted,—the plug 12^a forming a closure for the bearing member.

In the embodiment of the invention shown in Figures 16-18 the outer boiler sheet 1 is provided with an opening 5^a, an intermediate portion of the wall of which is rounded to provide a seat 6^a and the portion of said wall near the outer face of the boiler sheet may be beveled as at 7^a.

A ring 8^a is disposed in the opening in the boiler sheet and is made with a rounded portion 9^a having a universally movable bearing on the rounded portion 6^a of the wall of the opening in the boiler sheet. The under side of the ring 8^a may be made with an annular groove 10^a and said ring is provided with a tubular or cylindrical portion 11^a which is externally screw-threaded. A bearing member 12^a having an interior threaded portion is screwed onto the tubular portion 11^a of the ring and a gasket 13^a may be interposed between the inner end of said tubular portion 11^a and a shoulder 14^a in the bearing member. The outer end of the bearing member may be rounded as at 15^a and project into the groove 10^a. The bearing member is also rounded exteriorly as at 16^a for a purpose hereinafter explained. The ring is threaded interiorly near its outer end and receives a plug closure 17^a having an angular portion 18^a to receive a wrench, and a gasket 19^a may be disposed between said closure and a shoulder 20^a in said ring.

When the structure is mounted as above described it will be universally adjustable to insure proper alignment of the staybolt with its points of connection with respective boiler sheets and when properly adjusted it will be united to the boiler sheet by a weld 21^a which occupies a groove formed by the beveled portion 7^a of the wall of the opening in the boiler sheet and a beveled edge portion 22^a of the ring.

The bearing member 12^a may be mounted in a boiler sheet 1 as shown in Figure 17 and a cap or plug closure 23^a substituted for the ring 8^a and closure 17^a.

In the construction shown in Figure 18 the outer end of the bearing member 11^a may be flat and this end portion of the bearing member disposed between the wall of the opening in the boiler sheet and the cylindrical portion 11^a of ring 8^a and screwed to the same.

Having fully described my invention what I claim as new and desire to secure by Letters-Patent, is:—

1. A mounting for a staybolt, comprising a closure member and a bearing member removably connected with the closure member, said bearing member having a seat for the head of a staybolt and said closure member having a transversely curved exterior portion to seat on the wall of an opening in a boiler sheet.

2. A mounting for a staybolt, comprising a closure member and a bearing member having threaded connection therewith, said members having rounded exterior portions, and said bearing member having a seat for the head of a staybolt.

3. A mounting for a staybolt, comprising a hollow closure having an approximately elliptical cross section, and a bearing mem-

ber having threaded connection with said closure member, said bearing member having a seat for the head of a staybolt, and both of said members having exterior rounded portions.

4. In a staybolt structure, the combination with a boiler sheet having an opening, of a bearing structure mounted in said opening, said bearing structure comprising a closure member and a bearing member having threaded connection with said closure member, each of said members having an external configuration whereby the same may be mounted in the opening in the boiler sheet, and a staybolt having a head mounted in said bearing member.

5. In a staybolt structure, the combination with a boiler sheet having an opening, of a bearing structure comprising a closure member having an initially universally adjustable mounting on the wall of said opening and a bearing member having threaded connection with said closure member and having a seat for a bolt head, a staybolt having a head mounted in said bearing member, and a weld uniting said closure member to the boiler sheet.

6. In a staybolt structure, the combination with a boiler sheet having an opening, a portion of the wall of which forms a seat near the inner face of the boiler sheet, of a bearing structure comprising a closure member located in said opening with its outer extremity substantially flush with the outer face of the sheet and having a rounded peripheral portion mounted on the seat formed by the wall of the opening in the boiler sheet, and a bearing member having threaded connection with said closure member, and a weld located in the opening in the boiler

sheet and uniting said closure member to the boiler sheet.

7. A mounting for a staybolt, comprising a bearing member and a closure member removably connected together, each of said members having a rounded exterior portion for initial mounting in an opening in a boiler sheet.

8. In a staybolt structure, the combination with a boiler sheet having an opening, of a mounting for a staybolt comprising a bearing member and a closure member removably connected together, each of said members having an exterior rounded portion for initial universally movable mounting in the boiler sheet, a staybolt having a head mounted in said bearing member and a weld uniting said mounting to the boiler sheet.

9. A mounting for a staybolt, comprising a bearing member having an exteriorly rounded portion and interior seat for the head of a staybolt, said bearing member having an interior threaded portion, and a closure comprising a cap having a rounded peripheral portion and a threaded plug entering the threaded portion of the bearing member and having threaded connection with the cap within the latter.

10. In a staybolt structure, the combination with a boiler sheet having an opening, of a cap having an initially universally movable mounting in said opening, a bearing member entering said cap and threaded interiorly, a plug threaded into said bearing member and into said cap, a staybolt having a head mounted in said bearing member, and a weld uniting said cap to the boiler sheet.

In testimony whereof, I have signed this specification.

ETHAN I. DODDS.
